UNITED STATES PATENT OFFICE.

HANS CHRISTENSEN, OF SPRINGDALE, WASHINGTON.

CHURN.

1,344,937.

Specification of Letters Patent. Patented June 29, 1920.

Application filed July 23, 1919. Serial No. 312,811.

To all whom it may concern:

Be it known that I, HANS CHRISTENSEN, a citizen of the United States, residing at Springdale, in the county of Stevens and State of Washington, have invented new and useful Improvements in Churns, of which the following is a specification.

This invention relates to improvements in churns and is particularly adapted for 10 that class of churns in which the barrel or vat rotates about a horizontal axis. In this class of churns, kneading rollers have been employed onto which the material in the churn has been discharged and between 15 which such material was kneaded and worked. However, these constructions have been found to be objectionable because of the fact that these rollers could not be removed from the barrel to facilitate scalding and 20 cleaning the interior thereof. Therefore, while all the advantages of kneading rollers in the interior of the barrel have been fully appreciated, still, these advantages have been offset by the difficulty encountered 25 in readily cleaning the churn and barrel.

Now it is one of the primary objects of 30 my invention to employ these interiorly disposed kneading rollers and construct my improved churn so that the latter can be readily withdrawn for cleaning and sunning the same. It is also a feature of my invention to 35 rotatively mount the barrel in such a manner as to leave the axial portions thereof free and unobstructed thereby enabling me 40 to axially dispose the kneading rollers in the barrel instead of setting the kneading rollers off-center with respect to the barrel.

My invention includes a novel form of 45 drive whereby rotary motion imparted to the barrel to rotate the latter will be imparted also to the kneading rollers to rotate the latter about their individual axes. My improved driving means also provides for a power drive and also a manual drive, in either of which utilities the mechanism 50 serves the dual purposes of operating the barrel and the kneading rollers.

My invention also includes a novel means 55 whereby the kneading rollers may be securely mounted axially of the barrel in such a manner as to permit said rollers freely to rotate about their individual axes and preventing the rollers from bodily rotating, all of which will be more fully described in 60 connection with the accompanying draw-

ings, and will be more particularly pointed out in and by the appended claims.

In the drawings:

Figure 1, is a vertical sectional view of my improved churn. 60

Fig. 2, is a sectional view on line 2—2 of Fig. 1.

Fig. 3, is a view in side elevation, partly in section, showing the kneading rollers withdrawn from the barrel together with 65 parts pertinent to said rollers.

Fig. 4, is a plan view thereof, partly in section.

Fig. 5, is an end view looking in the direction of the arrow of Fig. 1. 70

Fig. 6, is a sectional view on line 6—6 of Fig. 1.

Fig. 7, is a sectional view on line 7—7 of Fig. 5.

Like characters of reference designate 75 similar parts throughout the different figures of the drawings.

A supporting frame is provided which may comprise vertical horses 1 and 2 each having one or more transverse braces 3 and 80 4. Longitudinal brace members 5 are shown to rigidify the frame. Supporting roller shafts 6 are also journaled in the horses and these serve to further strengthen the frame. Each shaft 6 has a pair of rollers 7 for 85 supporting the barrel rotatively to permit the latter to be revolved about a horizontal fixed axis and also to permit the barrel to be readily detached for shipping or moving. 90

As illustrated, the barrel 8 is cylindrical in form and is provided with a crank head 9 and an open head 10. A door 11 provides for removing the contents of the churn and the latter may have flanges 12 to hold the 95 barrel against longitudinal movement on the rollers 7. On the head 9 is a bearing 13 through which the spindle or shaft 14 of a crank 15, extends. The shaft 14 projects through the head 9 and slightly interiorly 100 of the barrel 8 to perform a supporting function which will be presently described, as regards its end 16. A set screw 17 serves to secure the shaft 14 so that when the crank 15 is turned, the barrel will be rotated. 105 This adjusting feature also provides for the shaft 14 being extended inwardly or outwardly, as desired. The barrel 8 is provided with a plurality of slats 18 which are equidistantly disposed in the interior thereof. 110

These slats are shown mortised endwise thereof into the heads 9 and 10 in slightly spaced relation to the cylindrical wall of the barrel. The purpose of these slats is to engage and elevate portions of the contents of the churn and then discharge those portions onto axially disposed kneading rollers, which will be presently described. A guard 19 is mounted on the head 9 and extends over the shaft 14 to prevent discharge of the contents thereon and beyond the ends of the kneading rollers. The head 10 is provided with an opening into which fits a closure 20 to completely close the barrel when the latter is being operated in the production of butter.

Reference will next be made to my improved kneading rollers and the manner of mounting the same.

As shown, these kneading rollers 21 and 22 are fluted so that when the material is delivered onto the same the freely meshing fluted portions will effectively knead the material. Roller 21 is mounted on spindle 23 and roller 22 is mounted on spindle 24. The head ends of said spindles are journaled in a spindle-supporting bar 25 having an opening 26 into which the end 16 of the crank shaft fits. Thus the head ends of the spindles are loosely supported on the crank shaft as the latter rotates freely in the opening 26 and the supporting bar 25 may be freely moved onto or out of engagement with said shaft. Said spindles extend through and are journaled in the closure 20. A frame bar 27 forms a bearing for the extreme ends of said spindles. Spindle 23 is provided with a gear wheel 28 which meshes with the gear wheel 29 on spindle 24 thereby insuring rotation of the rollers in opposite directions. On spindle 24, or fixed to gear 29, is a pulley 30. Closure 20 is rigidly although removably connected with bar 27 by means such as a guard 31 which is securely anchored to bar 27. Guard 31 is provided with a plurality of pins 32 and 33 which extend through the closure 20 so that the latter will be rigidly and non-rotatively fixed to the bar 27. It will thus be seen that with the parts in the position shown in Fig. 1, that when the bar 27 is secured to the frame member 2, the spindles 23 and 24 will be held in a horizontal position and will be prevented from sagging, the one with respect to the other. The engagement of the closure 20 with the opening and head 10 also serves as an additional support although this is not strictly necessary by reason of the ample support afforded by shaft 14.

I will next refer to the manner in which the bar 27 is secured to the frame, reference being had more particularly to Figs. 5 and 7.

Bolts 34 extend through the frame and bar 27 and may be provided with winged nuts 35. Wedges 36 may be interposed be-

tween the frame 2 and bar 27 to limit the extent of projection of the removable structure into the barrel and provide for a nicety of adjustment. In order to prevent longitudinal movement of the spindles 23 and 24, a retaining bar 37, pivoted at 38, on the bar 27, is adapted to take into annular grooves in the spindles, when in a position shown in Fig. 5. However, when the bar is released, the spindles may be withdrawn entirely. I may provide pins 39 to prevent disengagement of the spindles from the supporting bar 25.

I will next refer to the novel manner in which drive is imparted to the spindles. A countershaft 40 is journaled in bearings 41, 42 and 43, on the frame, and is provided with a pulley 44. A belt 45 is trained over this pulley and about the barrel 8. A pulley 46 on the free end of said shaft is connected into drive with pulley 30 by means of a belt 47. Thus as the crank 15 is turned, drive will be imparted through the barrel to the countershaft 40, and from the countershaft 40 by belt 47 to the spindle 24. If power-drive is desired a pulley 48 may be mounted on countershaft 40. Now it will be seen that the kneading rollers can be withdrawn, as shown in Figs. 3 and 4, by merely slipping the belt 47 endwise off from the pulley 46 and shaft 40.

It is believed that the advantages of my invention will be fully understood from the foregoing description, and while I have herein shown one specific form of my invention, I do not wish to be limited thereto except for such limitations as the claims may import.

I claim:—

1. A churn comprising in combination, a barrel having a crank and an open head, a frame, rollers on said frame rotatively supporting said barrel for rotation of the latter about a fixed axis, a crank projecting through said crank head and adjustably fixed to said head to rotate the latter, a spindle supporting bar loosely mounted on said crank, kneading roller spindles having their ends journaled in said supporting bar, a closure for said open head, a frame bar, said spindles extending through said closure and frame bar, a guard rigidly connecting said frame bar and closure, kneading rollers on said spindles between said closure and supporting bar, and means for operating said kneading rollers.

2. A churn comprising in combination, a supporting frame, a barrel rotatively mounted on said frame, and having a crank head and an open head, a crank having its shaft projecting through said crank head and adjustably fixed thereto, kneading rollers in said barrel having their crank head ends rotatively supported on said crank, a closure for said open end and a

frame bar rigidly united and rotatively supporting the remaining ends of said rollers, means for securing said frame bar to said frame to prevent bodily rotation of said 5 rollers except about their own axes and permit of withdrawal of said rollers from said barrel, and means for driving said rollers from said barrel.

3. A churn comprising in combination, a 10 supporting frame, a barrel rotatively mounted on said frame and having an open head end, kneading rollers for the interior of said barrel, and mechanism removably connected with said frame and a portion of 15 the interior of said barrel for inserting or withdrawing said rollers through said open head or withdrawing them out of said head.

4. A churn comprising in combination, a 20 supporting frame, a barrel rotatively mounted on said frame, and having an open head end, kneading rollers for the interior of said barrel, and mechanism removably connected with said frame and a portion of 25 the interior of said barrel for inserting or withdrawing said rollers through said open

head or withdrawing them out of said head, said mechanism including a closure for closing said open head end when said rollers are in position in said barrel.

5. A churn comprising in combination, a 30 rotatively mounted barrel having an open head end, kneading means for the interior of said barrel, and mechanism for mounting said kneading means in the interior of said barrel for insertion or withdrawal axially 35 through the head of said barrel.

6. A churn comprising in combination, a supporting frame, a barrel rotatively mounted on said frame and having an open head end, kneading means for the interior of said 40 barrel, and mechanism for supportingly connecting said kneading means with the frame for insertion and withdrawal of said kneading means axially through the head of said barrel, and means for operating said knead- 45 ing means when the latter is disposed interiorly of the barrel.

In testimony that I claim the foregoing as my own, I hereby affix my signature.

HANS CHRISTENSEN.
